UNITED STATES PATENT OFFICE.

CHARLES AUSTIN LESTER, OF WINONA, MINNESOTA.

REFLECTOR FOR AUTOMOBILE HEADLIGHTS, ETC.

1,417,926.

Specification of Letters Patent. Patented May 30, 1922.

Application filed April 13, 1920. Serial No. 373,546.

To all whom it may concern:

Be it known that I, CHARLES A. LESTER, a citizen of the United States, residing at 167 E. 7th St., Winona, county of Winona 5 and State of Minnesota, have invented certain new and useful Improvements in a Reflector for Automobile Headlights, etc., of which the following is a specification.

My invention relates to a reflector for automobile headlights, searchlights or similar devices, which is based upon the principle of reflection from a surface having as its elements parabolic curves of uniformly changing formulae. These elements are so combined and arranged that no reflected ray of light will rise higher than a horizontal line from the top of the headlight. Such a reflector is highly advantageous, in that it eliminates the glare from upwardly directed aberrant rays, which is both annoying and dangerous when such light falls upon a pedestrian or the driver of an automobile.

Two of the embodiments of my invention 25 will be illustrated in the following drawings and description which also disclose the principle of construction and operation thereof:—

Figs. 1 to 6 inclusive, are diagrammatic 30 views illustrating the mathematical principles upon which my device is based.

Fig. 7 is a perspective vertical sectional view of a practical device embodying the principles illustrated in Figs. 1 to 6.

Fig. 8 is a diagrammatic view illustrating the development of another embodiment.

Fig. 9 is an end view showing the same development.

Fig. 10 is a section of a reflector made according to the second embodiment.

Fig. 11 illustrates the zone of illumination of the reflector shown in Fig. 10.

In Fig. 1, the planes A, B and C are mutually at right angles to each other, so that 45 they intersect along the line xy , which is supposed to be horizontal, and along a vertical line perpendicular to this line xy .

Suppose that a paraboloid of revolution is constructed having its axis on the line xy , 50 its mouth being the circle 1, located in vertical plane A, so that the plane B passes through the axis thereof, and the plane A is at right angles to the said axis. This paraboloid is the ordinary parabolic reflector. 55 Let the focus of the paraboloid be denoted by F, the intersection of the paraboloid with

the plane B be denoted by P^1 and its intersection with the horizontal plane C, be denoted by 3. Assume that the planes B and C remain perpendicular to each other and 60 that they are revolved about the point F as the center, the plane A remaining stationary and perpendicular to plane B until the line of intersection mn between the revolved planes B and C, as shown in Fig. 2, makes 65 any required angle with the horizontal line xy which may be called the parabolic axis.

Now suppose, that a parabola which will be termed P^2 is constructed in plane B of Fig. 2 having its focus at F, its axis mn in 70 plane C as shown in Fig. 2 and the extremity of its upper limb coincident with the extremity of the upper limb of the original parabola described on plane B as shown in Fig. 1, and in Fig. 3.

75

The directrix of parabola P^2 is denoted by D^2 in Fig. 3 which illustrates such parabola and D^2 will be perpendicular to mn , and the resulting parabola will have its vertex at V^2 as shown in Fig. 3. This parabola 80 and all the others hereinafter described stop at the vertex in the reflector itself that is, only one limb thereof is used in constructing my new reflector. As clearly appears from Fig. 3, the original paraboloid of revolution was constructed by revolving the parabola P^1 , having the directrix D^1 .

Now suppose, that a parabola is drawn having its focus at F, line mn for its axis and the extremity of its lower limb coincident with that of the lower limb of P^1 . As 90 shown in Fig. 4, this last mentioned parabola is denoted by P^3 and its directrix D^3 is parallel to D^2 and its vertex will be at V^3 .

If now a figure is constructed in plane B 95 as in Fig. 5 having for its upper limb, the upper limb of P^2 and for its lower limb the lower limb of P^3 , its optical effect will be the same as the optical effect of a complete parabola having its axis on the line mn and focus 100 at F, but its upper and lower limbs will terminate at the ends of the upper and lower limbs of P^1 , and these terminal points will lie in the circle 1 shown in Fig. 1.

Hence, rays of light emitted from the 105 focus F will be reflected in a direction parallel to the line mn .

Suppose that the plane B in Fig. 2 is rotated about the line mn as an axis until it has made a quarter of a revolution, the line 110 mn at the same time turning or tilting on the point F as a pivot and always remaining in

a vertical plane, the plane revolving and the line turning with uniform velocity so that the line mn coincides with the line xy when the revolving plane B has completed its 5 quarter revolution. The movement of the axis mn is therefore always proportional to the movement of plane B.

As the revolving plane B assumes each of 10 a series of successive positions in the course of its revolution, suppose that a parabola is drawn therein having for its upper extremity a point on the circle 1 shown in Fig. 1, its focus at the common focus F, and for its axis a line forming with the line mn , the same fractional part 70 of the angle mFx as the fraction of the quarter revolution which has been completed by the revolving plane B.

As the vertex of a parabola is located in its 20 axis, all the vertices of the series of parabolas thus drawn, will be in a vertical plane such as plane B shown in Fig. 1; and the succession of points formed by the series of vertices will form a curved line extending from 25 V^2 to V^1 and denoted by R^1 as shown in Fig. 5. The value of the angle mFx as above explained will be decreased by $1/90$ thereof for every degree of revolution of the rotating plane B. Thus, if any number of degrees 30 through which the plane B has revolved is expressed by n , then the angle formed by the line mn at the same time with the fixed line xy is equal to the angle mFx minus $\frac{n}{90}$ of the 35 angle mFx .

Thus, if the angle mFx as shown in Figs. 2 and 3 is originally five degrees, then when the revolving plane B has revolved 45° , the line mn will have completed $\frac{1}{2}$ of its total 40 movement of 5° , and the angle made by it in its new position with the line xy will be $2\frac{1}{2}^\circ$.

Similarly, when the revolving plane B has revolved 18° , the line mn will have completed $\frac{3}{5}$ of its total movement, so that it will now 45 make an angle of 4° with the line xy .

When the construction has been brought to this point, the revolving plane B is horizontal and is perpendicular to plane A. From this position, suppose that the 50 revolving plane is revolved again through another quarter of a revolution about the line mn as an axis, the line mn which now coincides with the line xy , simultaneously turning uniformly about the point F as a center, 55 always remaining in the vertical plane, until it reaches again the position mn originally occupied by it in Fig. 2. Of course, the speed of the revolution of the plane B and the movement of line mn are always supposed to be uniform, therefore the same relation as before expressed will exist.

As the revolving plane occupies the succession of positions in the second quarter of its revolution, suppose that a parabola is 60 constructed thereon in each of its positions

having for its lower extremity a point in the circle 1 which is shown in Fig. 1, its focus at the common focus F, and for its axis a line on the vertical plane B, the said line forming with the line xy , the same fractional part 70 of the angle mFx as the fraction of the quarter revolution which has been completed by the revolving plane.

All the vertices of the second series of parabolas form a line in the vertical plane 75 designated by R^2 shown in Fig. 5.

The revolving plane B now having finished half of a revolution, again occupies the position shown by plane B in Fig. 2 and one half of the reflector has been completed. 80 The other half may be completed in the same way by revolution of the vertical plane in the opposite direction in a similar manner and the complete reflector is thus formed.

The surface of this reflector has a continuously varying curvature of such a kind that it may be described as a variable parabolic surface of continuous curvature consisting of an innumerable number of parabolic curves constructed on a variable axis, 85 every axis being in a vertical plane, and every parabola having a common focus. This surface so completed may be used as a reflector for auto headlights or the like by inserting through its vertex as diagrammatically shown in Fig. 6, a cylindrical socket for holding a lamp so that the axis of the cylinder coincides with the axis of the original paraboloid of revolution P^1 shown in Fig. 1, and the lamp may be 90 placed in such position as to bring its filament in adjustment at the common focus, as shown diagrammatically in Fig. 6 and in perspective in the vertical sectional view 95 shown in Fig. 7.

Another form of this reflector, which is more practicable mechanically, is developed as follows:

Construct a parabola of the desired formula on vertical plane B, Fig. 1 and let the 110 circular mouth of the resulting paraboloid of revolution lie in plane A, as before. This may be considered as the basis or basic parabola from which the new reflector is to be formed. Let its focus F and its axis xy , lie 115 in the line of intersection of planes B and C shown in Fig. 1. Now revolve the two planes A and C on F as a pivot in such a way that planes A and C remain perpendicular to each other and plane B remains 120 perpendicular to plane A, until line of intersection of planes A and C makes any required angle with their original line of intersection, as shown by line mn Fig. 2, as before described. The parabola described 125 on plane B will then assume the position P^2 Fig. 8. It will be noted that in Fig. 8 the focus is the same point in both positions of the parabola, but the upper limit of the upper limb projects beyond plane A and 130

the extremity of the lower limb does not extend to plane A. The lower limb is to be extended until it reaches plane A, and the upper limb is to be shortened an equal amount. P^2 is now rotated about its axis, the axis at the same time being turned about F as a center, and remaining in plane B, the two movements to be simultaneous and in such a ratio that one quarter of a revolution will be accomplished at the same time that line mn coincides with line xy . This ratio may be such that the revolving parabola will complete each fractional part of its quarter revolution at the same time that 10 the line mn completes the same fractional part of its complete movement toward line xy , or the movement of the line mn may be in a constantly accelerated or a constantly retarded ratio to the movement of the parabola, but in any event the two movements are to terminate at the same time. When P^2 has reached the horizontal by completing one-quarter revolution it will coincide with P^1 in the horizontal axial plane of the basic 20 paraboloid of revolution. Now continue the revolution of P^2 on its axis, and let the axis turn vertically on the focus as a pivot as before, but in a direction toward line mn , the two movements having the same 25 ratio as before described so that when P^2 has reached a perpendicular position the axis mn which had coincided with xy will again assume position mn , and P^2 will be in the original position it occupied before 30 starting the development of the new modified parabolic surface. This surface is one in which every element is a parabola of the same formula and curvature, having a constantly changing axis and a common focus. 35 The other half of the reflector is formed by correspondingly revolving the parabolic generatrix in the opposite direction. This modified paraboloid of revolution is now to be limited by plane A, and its vertical 40 central section through plane B is shown by curve F' , V^2 , G , Fig. 8. This curve is a parabola with vertex at V^2 , its upper limb shorter than the lower. If now in Fig. 8 that part of the figure representing the 45 surface of plane B is considered to represent the surface of plane C, a section of the paraboloid in plane C will correspond to the original parabola as shown at D, V' , E. The opening or mouth of the reflector 50 will be a curved figure almost circular in outline lying in plane A, as shown in Fig. 9. Angle $mF'x$ Fig. 8 is much exaggerated for clearness, amounting in the diagram to about 7 degrees, whereas in actual practice 55 it would need to be about $2\frac{1}{2}$ degrees. Hence the difference in the length of the two vertical arms of the parabola F' , V^2 , G , Fig. 8, and the distortion of the mouth of the reflector A, in Fig. 9, are also much exaggerated. Fig. 10 is a sectional drawing of 60

the completed reflector through the vertical axial plane, showing bulb in position. The eccentricity of the bulb in Figs. 9 and 10 is exaggerated in the same degree. The outer edge of the flange is indicated by circle 70 B, Fig. 9.

The principle upon which this reflector is constructed is as follows:—

If light from an automobile headlight with its axis horizontal is thrown on a wall 75 or screen at a given distance (as 50 ft.) away, the outline of the illuminated area is circular or approximately so, greater in diameter than the diameter of the headlight, its center the same height from the ground 80 as the focus of the reflector. The highest point of the area is that point in its vertical diameter, which is illuminated by those rays from the top of the vertical axial section of the reflector which deviate most widely from 85 parallelism with the axis. In order to bring the top of the circle of light to a point the same distance from the ground as the top of the headlight, it is necessary to point the headlight downward until its axis forms the 90 same angle with its original horizontal position as the angle of deviation of the rays which reach the top of the circle. For instance if the rays deviate 5 degrees, the axis must be inclined five degrees from the horizontal. This lowers the whole pattern or 95 circle of light so that in practice the most brilliant illumination is cast on the ground too close to the car. But the rays which emanate from the horizontal axial section 100 illuminate the horizontal limits of the circular pattern, and with the headlight in its original position they are already horizontal, and the headlight needs no tilting to keep them from rising and ultimately 105 blinding the approaching driver or pedestrian. That is, the rays from the vertical meridian deviate 5 degrees from parallelism with the horizontal axis, and also rise from the ground at an angle of 5 degrees, but the 110 rays from the horizontal meridian or section of the reflector deviate from parallelism with the axis but do so transversely, and remain parallel to the ground. In the same manner, rays from any other meridian of the 115 reflector rise from parallelism with the ground in proportion to the position of the given meridian. Thus, rays from the 45 degree meridian will deviate 5 degrees from the axis, but will only make an angle of $2\frac{1}{2}$ 120 degrees from the ground. This can readily be demonstrated by cutting in a piece of cardboard a slot $\frac{1}{4}$ of an inch wide and as long as the diameter of the mouth of the reflector, and placing it in front of the reflector and turning it in different positions and noting the position of the band of light falling on the wall or screen. Hence if the vertical meridian of the headlight could be tilted 125 5 degrees the horizontal meridian left 130

horizontal, and the 45 degree meridian tilted but $2\frac{1}{2}$ degrees, and at the same time all other meridians tilted their proper proportional angle, the highest rising ray from 5 every point on the reflector would be brought horizontal, and a massing of horizontal rays would occur which would preserve the brilliancy of the horizontal beam and at the same time no ray would rise above a line 10 parallel to the horizontal axis. The reflector herein described is equivalent in the manner in which the rising rays are brought to parallelism to an ordinary parabolic reflector gradually tilted so that rising rays 15 from each meridian in turn becomes horizontal. Fig. 11 shows diagrammatically the modification of the illuminated area when the new reflector R is used, with the greatest intensity of illumination retained in approximately the same position as with the ordinary reflector, but no rays rising above a line parallel with the top of the headlight. The lines A' and B' in Fig. 11 denote the 20 limits of the light from an ordinary headlight which throws the circular pattern C of light. The pattern of light cast by the new reflector is shown by M, the relative intensity being indicated by N.

I claim:—

- 30 1. A parabolic reflector having its surface composed of parabolic elements whose axes make different angles with the main axis of the reflector, the angle made by the axis of any given element being proportional to the 35 angle made with the vertical meridian by the meridian in which such element is located, the axes of all said parabolic elements being located in the same plane.
2. A parabolic reflector having its surface 40 composed of parabolic elements whose axes make different angles with the main axis of

the reflector, the said angles varying in a uniform series in each quadrant of the reflector, the angle made by the axis of any given element being proportional to the angle made with the vertical meridian by the meridian in which such element is located, the axes of all said parabolic elements being located in the same plane. 45

3. A reflector having a continuously 50 curved reflecting surface, capable of being divided into halves each half being the complement of the other, said surface being developed by the half revolution of a parabola about its axis, said axis being moved simultaneously with the revolution of the parabola, in such a way that during one quarter revolution said axis is moved in a direction away from its original position, and during the next quarter revolution toward its initial 55 position, each arc of the parabola during the described movements developing one half of the reflector, thus by the movement of the whole parabola producing the entire surface.

4. A reflector having a reflecting surface 60 composed of a series of parabolic elements having a series of axes, all in the same vertical plane, which make different angles with the main axis of the reflector, the angle made by any given axis with the said main axis 65 increasing in each quadrant in a given ratio to the angle made by said element with a horizontal plane passed through said main axis, whereby when said main axis is held in the horizontal plane the highest-rising 70 rays reflected from any given point on the surface of the reflector are caused to assume a substantially horizontal position. 75

In testimony whereof I hereunto affix my signature.

CHARLES AUSTIN LESTER.
